SPACE CURRENT DEVICE

Application filed September 26, 1925, Serial No. 58,843, and in Germany October 6, 1924.

My invention relates to space-current devices and it has particular relation to high-vacuum tubes in which the current is carried principally by electrons.

5 High-vacuum electron tubes, which have the great advantage of being susceptible of a very close control of the current between the cathode and the anode, by controlling the space charge therebetween, are limited in 10 their capacity because of the limited number of electrons that can be emitted from the incandescent cathodes heretofore utilized in such tubes.

The principal object of the present invention is to provide a space-current tube in 15 which the current is carried principally by electrons and which is capable of operating with much larger currents than those heretofore used. According to my invention, the electrons utilized to carry the current between the cathode and the anode are supplied 20 from a gaseous discharge, such as an arc or a glow discharge, in a different portion of the tube, wherein conduction takes place principally by means of ionized gaseous particles. The tubes are so constructed as to restrict the 25 arc or gaseous discharge to its own portion of the tube, thus obtaining a substantially pure electron discharge through the vacuum space to the main anode. The tube may be provided 30 with control electrodes such as grids, and the electron current in the tube may be readily adjusted by controlling the potential of the grids or by any other known means for 35 controlling the current in a substantially pure electron discharge.

Referring to the drawing, Fig. 1 is a sectional view of an electron tube embodying my invention, and

40 Figs. 2 and 3 are similar views of electron tubes embodying modifications of my invention.

Referring to Fig. 1, a cylindrically shaped envelope 1 of insulating material, such as 45 glass, has a depending portion 2 containing a mercury cathode 3 with which contact is made by means of a terminal wire 4. The top of the cylindrical envelope is provided with an extension 5 in which is mounted a solid electrode 6 held upon a sealed-in terminal wire

7. The solid electrode 6 is arranged to act as an auxiliary anode for maintaining an arc discharge with the mercury electrode 3. A cylindrical main anode 8 is mounted within the envelope 1, surrounding the arc path 9 55 extending between mercury cathode 3 and the auxiliary anode 6.

The main anode 8 is separated from the mercury arc path 9 by a cylindrical separator-wall or partition 11, dividing the interior of 60 the envelope 1 into a central longitudinal cathode chamber 12 extending between the mercury cathode and the auxiliary anode 6, and an anode chamber 13 surrounding the 65 middle portion of the cathode chamber.

To operate the device, a mercury arc discharge 9 is maintained between the mercury cathode 3 and the auxiliary anode 6 by means of an energy source 14. The partition or separator 11 which surrounds the mercury 70 arc discharge 9 is so constructed as to permit the passage of electrons from the arc discharge towards the main anode 8, while preventing the passage of gas particles into the main anode chamber 13. The action just 75 mentioned is obtained by providing the cylindrical periphery of the separator 11 with openings 15 which are inclined in such manner that the vapor stream from the mercury cathode 3 to the anode exercises a pumping 80 or evacuating action upon the space of the main anode chamber, tending to maintain a high vacuum in the main anode chamber.

The electron flow from the arc discharge will not be seriously impaired by the suction 85 action exercised by the mercury vapor, while the heavier molecular particles of the vapor and residual gases are sucked into the inner chamber by the upwardly streaming mercury vapor blast. An electron current of large 90 capacity may thus be obtained by connecting a load 16 in series with an energy source 17 between the anode 8 and the mercury cathode 3.

The electron current flowing between the 95 arc discharge 9 and the main anode 6 may be controlled by means of auxiliary electrodes placed in the space between the arc discharge and the anode. In the electron tube shown in Fig. 1, the partition 11 surrounding the 100

arc discharge is utilized as a control electrode, the potential of the partition 11 being controlled by means of a switch 18 placed in series with a source of control energy 19.

5 By utilizing an arc or gaseous discharge as an electron-emitting electrode, in accordance with my invention, it is possible to obtain much larger electron currents than by utilizing an incandescent solid electrode. At 10 the same time, the current between the arc discharge and the main anode retains the character of a pure electron discharge, through the evacuating action of the vapor blast in conjunction with the perforations in 15 the partition surrounding the arc discharge, the evacuating action being similar to that of a vapor diffusion pump.

To obtain an increased evacuating action 20 in the main anode chamber 13, the upper extension 5 of the envelope may be utilized as a condensation chamber for the mercury vapor, thus increasing the velocity of the vapor blast. To this end, the upper extension 5 around the auxiliary anode 6 is surrounded 25 by a jacket 21 through which a cooling liquid 22 is circulated. The container 1 may be further evacuated by connecting a tubular extension 23, leading from the interior of the upper chamber 5, to a suitable vacuum pump, 30 not shown in the drawing.

In a modification of my invention shown 35 in Fig. 2, the arc discharge is maintained between an auxiliary solid anode 25, which is mounted on the bottom of a cylindrical envelope 26, and a mercury cathode 27, which is contained in a grooved portion 28 of a pear-shaped extension 29 on the top of the envelope 26. The space of the arc discharge between the auxiliary anode 25 and the mercury 40 cathode 27 is enclosed by a porous diffusion diaphragm 30 of cylindrical shape, the main anode 31 surrounding the diffusion diaphragm.

I have found that a diffusion diaphragm, 45 of the kind used in osmotic processes, very effectively prevents gaseous molecules from passing into the anode chamber on account of the relatively great volume and large mass of the gas particles. On the other hand, the diaphragm presents very little resistance to the flow of electrons therethrough from the arc discharge toward the main anode 31. As a material for the diaphragm, I may use unglazed porcelain or a similar ceramic material. The diaphragm may also be made of 50 other semi-conductors or non-conductors such as, rare earths, compounds of aluminum, magnesium and similar light metals, or other material having similar characteristics.

55 In order to increase the flow of electrons toward the anode, the diaphragm may be maintained at incandescence by suitably heating the same.

60 The stream of the mercury vapor along 65 the walls of the diaphragm 30, produces an

evacuating action similar to that obtained in the construction shown in Fig. 1. The flow of electrons between the diaphragm 30 and the anode 31 may be controlled by means of an electrode 32 disposed therebetween. 70

In a modification of my invention shown in Fig. 3, a discharge tube having a depending bottom portion 41, similar to that of Fig. 1, is provided with a pear-shaped upper extension 42, similar to that of the device 75 shown in Fig. 2, containing a mercury electrode 43 which is used in conjunction with a second mercury electrode 44 disposed in the bottom portion 41, to maintain an arc discharge which supplies the electrons through 80 a porous diaphragm 45 similar to that in Fig. 2. The diaphragm 45 is shown provided with a heating coil 46 for maintaining the same at a temperature at which it will increase the electron flow toward the anode 85 47.

The several modifications shown and described hereinabove are only illustrative of the broad principles utilized in the construction of a space-current device wherein a pure 90 electron discharge is maintained by means of an auxiliary gaseous or arc discharge serving as a cathode, and it is desired that the appended claims shall be broadly construed to cover all modifications falling within the 95 spirit of my invention.

I claim as my invention:—

1. A space-current device having an envelope and comprising a diffusion diaphragm dividing said envelope into an anode chamber and a cathode chamber, an anode mounted in said anode chamber, two electrodes mounted in said cathode chamber, for maintaining a gaseous discharge in said cathode chamber, said diffusion diaphragm permitting a flow of electrons from said discharge to said anode, but obstructing the flow of gaseous ions therebetween. 100

2. A space-current device comprising a hermetically closed envelope, a diffusion diaphragm dividing said envelope into an anode chamber and a cathode chamber, an anode in said anode chamber, said anode chamber to be maintained at a high vacuum, a mercury cathode and a cooperating electrode in said cathode chamber, said diffusion diaphragm having openings adjacent the periphery of the stream of mercury vapor from said cathode. 110

3. A space-current device comprising an evacuated envelope, a separator dividing said envelope into an anode chamber and a cathode chamber, a main anode in said anode chamber, a mercury cathode and an auxiliary anode in said cathode chamber for maintaining an arc-discharge, said separator having openings to cause a pumping action by the stream of mercury vapor from said cathode, a portion of said cathode chamber extending within said anode chamber and the 120 125 130

remaining portion extending outside said anode chamber.

4. A space-current device comprising an evacuated envelope, a separator dividing said envelope into an anode chamber and a cathode chamber, an anode in said anode chamber, and a mercury cathode and an auxiliary anode in said cathode chamber for maintaining an arc-discharge, said separator having very small passages for preventing the passage of conducting vapor from said cathode chamber to said anode chamber but permitting a flow of electrons therebetween, a portion of said cathode chamber being surrounded by said anode chamber and the remaining portion extending outside said anode chamber.

In testimony whereof, I have hereunto subscribed my name this 5th day of September 1925.

RUDOLF G. BERTHOLD.
